U.S. Appl. No. 29/816,885, Pet Collar, filed Nov. 25, 2021.

Primary Examiner — Aula Soroush(74) *Attorney, Agent, or Firm* — Perry + Currier Inc.(57) **CLAIM**

The ornamental design for a pet collar, as shown and described.

DESCRIPTION

FIG. 1 is a perspective view of the pet collar showing our new design;

FIG. 2 is another perspective view thereof;

FIG. 3 is a right side elevation view thereof;

FIG. 4 is a front elevation view thereof;

FIG. 5 is a left side elevation view thereof;

FIG. 6 is a rear elevation view thereof;

FIG. 7 is a top plan view thereof; and,

FIG. 8 is a bottom plan view thereof.

The broken lines illustrate portions of the pet collar that form no part of the claimed design.
